BILLFOLD

Robert N. Lupfer and William R. Whitmer, Springfield, Ohio, assignors to The Springfield Leather Products Company, Springfield, Ohio, a corporation of Ohio

Application January 28, 1954, Serial No. 406,787

11 Claims. (Cl. 150—38)

This invention relates to wallets and particularly to wallets which include a combination of features such as a billfold, pockets for a card case and writing pad, pencil, coin purse and so forth.

A primary object of the invention is the provision of a novel structural arrangement of the component parts of the wallet which permits the same to be readily folded into a compact assembly.

A further object of the invention is the provision of a panel having a novel readily foldable facing portion which materially improves the compactness of the wallet.

An important object of the invention is the provision of the panel in longitudinal portions which are slidably connected longitudinally to permit independent sliding movement of each of the portions at wallet folds.

The invention will be more fully understood by reference to the following detailed description and accompanying drawing wherein:

Figure 1 is a perspective view of the wallet in a closed position thereof;

Figure 2 is a perspective view of the wallet in a partially opened position thereof;

Figure 3 is a view of the principal parts of the wallet before the parts have been folded together;

Figure 4 is a view illustrating the manner in which the panel is secured to the inner wall of the wallet at one end thereof;

Figure 5 is a view illustrating the manner in which the panel is secured at the other end thereof; and

Figure 6 is a perspective view of a portion of the structure of Figure 2.

Referring to the drawings the numeral 1 represents the flexible outer wall of the wallet which is preferably of leather or similar flexible material. Outer wall 1 extends longitudinally of the wallet and has secured to the lower edge thereof and preferably integral therewith an inner flexible wall shown generally at 3 comprised of pocket forming members 5, 7 (Figure 3).

Outer wall 1 at the upper edge has a small flap 9 (Figure 3) which is folded over in the assembled condition of the wallet and secured to the internal side of the outer wall to provide a good finished appearance; a similar flap 11 is provided at the bottom edge adjacent the member 5 for the same purpose.

A snap fastener indicated at 13 is provided to hold the wallet in the closed position shown in Figure 1. Adjacent the snap fastener the outer wall is turned on each side of the fastener to provide flaps 15, 17 (Figure 2). An intermediate panel or strip 19 of the wallet extends beneath these turned flaps, receives a portion of fastener 13 therethrough and is fixedly secured to the outer wall by the turned portions, as with stitching or a suitable adhesive.

The panel 19 extends longitudinally of the wallet and is formed in two portions, a facing portion 21 which overlaps another portion 22 and which latter portion is slidably secured to member 7 as described hereinafter.

Facing portion 21 at its right hand end (Figure 3) is

2

provided with a tongue 23 which slidably engages through the transverse cutout loop 25 of portion 22, the tip 27 of the tongue being enlarged to lock with the loop and to prevent separation of portions 21, 22.

5 The right hand end of portion 21 at the upper side thereof is also provided with a hooked tongue 29 which is slidable longitudinally in the slot 31 of portion 22, the hooked end 33 passing through the slot and extending leftwardly of the slot slightly (Figure 3) to prevent undue movement of the portions 21, 22 transversely of the wallet length.

The right hand end of portion 22 above the longitudinal center line thereof is cut out to provide a substantially T-shaped member 35 bounded by slots 36, 37 and slits 38, 39. The head of the T in the assembly of the wallet is turned on itself slightly and passes first through aperture 40 and then aperture 41 of flap portion 43 of member 7 (Figure 5) which flap portion is bent over the upper edge of portion 22 and down the rear thereof to effect the engagement; the portion 22 is thus slidably connected with the inner wall.

20 The member 7 is itself provided with a pair of slits to define a loop 45 and in the engaged position of T-shaped member 35 member 7 and the loop 45 lie transversely over portion 22 and the loop 45 receives an extended end 47 (Figures 2 and 3) of outer wall 1.

25 Member 5 of the inner wall 3 is provided with a flap portion 49 which carries tab 51 and the flap portion 49 is folded over panel 19 (Figure 4) and the tab 51 engages in the slot 53 formed by the cutting out of loop 25 (Figure 3) from portion 22.

30 Summarizing the connecting relations, the outer wall is secured to facing portion 21, while the facing portion, and members 5 and 7 constituting the inner wall are secured to portion 22—the securing of the facing portion and member 7 being such as to provide for longitudinal movement of portion 22.

35 The formation of the panel 19 in two portions each of appreciable length and the positioning of the sliding connection between the portions at a point remote from the end portion of the wallet, and preferably beneath an inner wall member, is important as it avoids a multiplicity of layers of leather or the like at a point where the wallet is to be folded as well as providing a finely finished flexible facing portion. The requirement of flexibility is dictated by the plurality of elements which the wallet is designed to conveniently carry.

40 Thus as may be seen from Figures 2 and 6 a pencil and pad of paper are readily insertable into the structure, a pair of slits 55 being formed in inner wall member 5 to receive a backing of paper pad 57 therethrough. The pencil is retained by a suitable leather holder 59 itself secured to the wall by tab 61 passing through a slit in member 5.

45 The numeral 63 (Figure 2) indicates an area of fold in the panel 22 between the inner wall members 5 and 7.

50 There has thus been provided in the structure of invention an intermediate panel consisting of two principal parts which is effective to not only secure the inner wall and outer wall of the wallet together but is so constructed and arranged that the flexibility of the wallet itself is not affected detrimentally by the insertion of the panel member. Thus in two-fold billfolds one sliding connection permits independent sliding movement of the panel portion at one folding point while the other sliding connection permits independent movement at the other sliding point and in addition the arrangement is such that one of the two portions of the panel member forms the interior facing of the flap of the wallet.

55 It will be understood that this invention is susceptible to modification in order to adopt it to different usages and conditions and accordingly, it is desired to com-

prehend such modifications within this invention as may fall within the scope of the appended claims.

We claim:

1. A wallet comprising inner and outer walls secured together along one edge, the inner wall extending over only a portion of the length of the outer wall and defining a longitudinal spacing with an end of the outer wall, and an intermediate panel extending longitudinally of the wallet having a foldable facing portion extending across said spacing and fixedly secured to said end of the outer wall, the intermediate panel being formed in longitudinally extending portions, including the facing portion, and having a longitudinally slidable connection therebetween.

2. A wallet comprising inner and outer walls secured together along one edge, the inner wall extending over only a portion of the length of the outer wall and defining a longitudinal spacing with an end of the outer wall, and an intermediate panel secured between the walls extending longitudinally of the wallet having a foldable facing portion extending across said spacing and fixedly secured to said end of the outer wall, the intermediate panel being formed in longitudinally extending portions including the facing portion and having a longitudinally slidable connection between the portions and under the inner wall.

3. A wallet comprising inner and outer walls secured together along one edge, the inner wall being of lesser length than the outer wall and defining a longitudinal spacing with an end of said outer wall, said inner wall comprising spaced pocket-forming members, and an intermediate panel secured between the walls extending substantially the length of the wallet and fixedly secured to said end of the outer wall and cooperating with the pocket-forming members to define pockets, the intermediate panel being formed in longitudinal portions having a longitudinally slidable connection securing the same together.

4. A wallet comprising inner and outer walls secured together along one edge, the inner wall being of lesser length than the outer wall and comprising a pair of longitudinally spaced members, one of which defines a longitudinal spacing with an end of the outer wall, and an intermediate panel extending substantially the length of the wallet and having a foldable facing portion fixedly secured to said end of the outer wall, said facing portion bridging the spacing between said end of the outer wall and the one said member, the intermediate panel being formed in two longitudinal portions including the facing portion and having a longitudinally slidable connection securing the said portions together.

5. A wallet comprising inner and outer walls secured together along one edge, the inner wall extending over only a portion of the length of the outer wall and defining a longitudinal spacing with an end of the outer wall, and an intermediate panel between the walls extending longitudinally of the wallet having a foldable facing portion extending across said spacing, the panel being fixedly secured at one end to said end of the outer wall and slidably secured at the other end to the inner wall, said intermediate panel being formed in longitudinally extending portions, including the facing portion, and having a longitudinally slidable connection therebetween.

6. A wallet comprising inner and outer walls secured together along one edge, the inner wall being of lesser length than the outer wall and comprising a pair of longitudinally spaced members, one of which defines a longitudinal spacing with an end of the outer wall, and an intermediate panel extending substantially the length of the wallet formed in longitudinal portions one of which bridges said spacing and is fixedly secured to said end of said outer wall and the other of which is slidably secured to the other of said pair of longitudinally spaced members of the inner wall, said panel portions having a longitudinal slidable connection securing the same together.

7. A wallet comprising inner and outer walls secured together along one edge, the inner wall extending over only a portion of the length of the outer wall and defining a longitudinal spacing with an end of the outer wall, a secured intermediate panel extending longitudinally of the wallet having a foldable facing portion extending across said spacing and fixedly secured to said end of the outer wall, the intermediate panel being formed in longitudinally extending portions including the facing portion having a longitudinally slidable connection therebetween, said portions also having a transverse connection to inhibit swiveling of the portions.

15 8. A wallet comprising inner and outer walls secured together along one edge, the inner wall comprising a pair of spaced pocket-forming members one of which defines a longitudinal spacing with an end of the outer wall, and an intermediate panel secured between the walls extending substantially the length of the wallet across the spacing and fixedly secured to said end of the outer wall and cooperating with the pocket-forming members to define pockets, the intermediate panel being formed in two longitudinal portions having a slidable connection securing the same together, and one of the pocket-forming members having a flap portion and a tab extending therefrom, the flap portion being folded over the panel and the tab being slidably secured thereto.

20 9. A wallet comprising inner and outer walls secured together along one edge, the inner wall comprising a pair of spaced pocket-forming members one of which defines a longitudinal spacing with an end of the outer wall, and an intermediate panel secured between the walls extending substantially the length of the wallet across the spacing and fixedly secured to said end of the outer wall and cooperating with the pocket-forming members to define pockets, the intermediate panel being formed in two longitudinal portions having a slidable connection securing the same together at a point remote from the said spacing and beneath the one said pocket-forming member, the one said pocket-forming member having a flap portion 25 extending therefrom foldable over the upper edge of the intermediate panel, the intermediate panel being slidably secured to said flap portion, said intermediate panel having a slot therein and said flap portion having a tab engageable in the slot, the tab and slot forming a sliding connection between the intermediate panel and flap portion.

40 10. In a wallet, inner and outer walls and an intermediate panel therebetween, the panel being formed in two longitudinally extending portions, the inner wall being also formed in two longitudinally extending members defining a pair of spacings along the wallet length with the outer wall, the panel extending across the spacings and defining with the outer wall at the spacings transversely extending folds, the two panel portions having a longitudinally slidable connection therebetween and one being fixedly secured at an end to the outer wall and the other portion being slidably connected to the inner wall for independent longitudinal panel movement at the folds.

45 11. In a wallet, inner and outer walls and an intermediate panel therebetween, the intermediate panel and the outer wall having adjacent ends thereof secured together forming a closed end of the wallet, the inner wall extending over a portion of the length of the outer wall and defining with said closed end of the wallet a spacing, the panel being formed in two portions extending longitudinally of the wallet and having a longitudinally slidable connection therebetween, one of the panel portions being a foldable facing portion and extending across said spacing.
